UNITED STATES PATENT OFFICE.

FRANK M. THOMSON, OF JERSEY CITY, NEW JERSEY.

PISTOL-HOLSTER.

SPECIFICATION forming part of Letters Patent No. 229,208, dated June 22, 1880.

Application filed May 8, 1880. (Model.)

To all whom it may concern:

Be it known that I, FRANK M. THOMSON, of Jersey City, in the county of Hudson and State of New Jersey, have invented a certain 5 new and Improved Holster; and I do hereby declare the following to be a full, clear, and exact description of the same, reference being had to the accompanying drawings, forming part of this specification, in which—

10 Figure 1 is a perspective view, and Fig. 2 an end view.

Similar letters of reference in the several figures denote the same parts.

My invention has for its object to provide 15 an improved holster, into which a revolver or pistol can be easily and quickly slipped, and which will hold the revolver securely when entered, and from which the revolver can be readily disengaged and withdrawn when de- 20 sired, without the necessity of undoing flaps, straps, or other fastening devices, as in the common holster.

To this end my invention consists of a holster composed of leather, rubber, paper, vul- 25 canized fiber, or other flexible material, having a laterally-contracted mouth which expands to permit the entrance of the revolver, but contracts again after the revolver is fully en- 30 tered, so as to clasp the revolver back of the cylinder or the enlargements on its sides, and thus securely hold it until withdrawn by a positive pull upon it.

It further consists in the peculiar manner 35 of constructing the contracted mouth, all which I will now proceed to describe.

In the drawings, A represents the body of 40 the holster or case, composed of leather, rubber, paper, vulcanized fiber, or other suitable flexible material, though preferably of leather, and of the general form of the ordinary holster.

The lateral sides s s of the mouth are rounded 45 down to the ends a a' in the manner shown, and each side is slotted near the end a, and the parts b b, adjoining the slits, overlapped and secured together by sewing and rivets, or otherwise, thus producing a contraction or convergence of the sides, and causing shoulders b' b' to be formed at the inner ends of the slits,

as shown. The sides s s are made curved or 50 rounded, for the purpose of enabling them to open and close more readily.

Where paper, rubber, &c., are used in the construction of the holster, the whole article may be molded in one piece, and the neces- 55 sity of slitting the sides to contract them obviated.

As the revolver is forced into the holster the flexible sides yield and expand till the cartridge-cylinder has passed them, where- 60 upon they again contract and close around the cylinder, with the shoulders b' b' in rear thereof. The revolver is thus held securely within the holster until withdrawn by a positive pull upon it. 65

To facilitate the introduction and removal of the revolver, the ends a a' of the mouth of the holster may be pressed slightly toward each other; but this is not necessary, as either operation can be easily performed without 70 touching the holster with the hand at all.

Cases for carbines, rifles, and shot-guns can be made on the same principle as the revolver-holster, it being only requisite that the form of the article be slightly varied to adapt it to 75 the different styles of fire-arms.

The invention may also be embodied in the form of a knife-case or sheath for knives which have lateral projections at the base of the blade or on the handle, as will be ap- 80 parent.

Where the holster is made of leather, as shown in the drawings, the seam which terminates at the end a' of the mouth is prefer- 85 ably re-enforced by a strap, c, and an ordinary belt-loop, d, is also applied to the side of the holster, as shown.

I claim as my invention—

1. A holster constructed of leather or other flexible material and having an open mouth 90 whose lateral sides are contracted or converged, as shown, so as to form shoulders, behind which the enlargements of the weapon lie when the latter is entered, substantially as described, for the purpose specified. 95

2. A holster composed of leather or other flexible material and having a laterally-con- 95 tracted mouth, formed by slitting the sides of

the mouth and overlapping and securing the parts adjacent to the slits, substantially as described.

3. The holster having the lateral sides of its mouth slitted and overlapped near the end *a* of the mouth, so as to form shoulders *b' b'*, substantially as described, for the purpose specified.

4. The holster having the sides of its mouth contracted and the edges of said sides rounded or curved from point *a* to point *a'*, substantially as described, for the purpose specified.

FRANK M. THOMSON.
